DESIGN.

E. TODD.

Pencil-Cases.

No. 7,006.

Patented Dec. 2, 1873.

L. Marshall
W. J. Winberg

Edward. Todd

UNITED STATES PATENT OFFICE.

EDWARD TODD, OF BROOKLYN, NEW YORK.

DESIGN FOR PENCIL-CASE.

Specification forming part of Design No. 7,006, dated December 2, 1873; application filed November 1, 1873.
[Term of Patent 3½ years.]

To all whom it may concern:

Be it known that I, EDWARD TODD, of Brooklyn, in the county of Kings, State of New York, have invented a certain new and original Design for Pencil-Cases; and do hereby declare that the following is a full, clear, and exact description thereof, reference being had to the accompanying drawing making a part of this specification, in which is shown a perspective view of my improved case.

The distinctive features of my invention consist in a case having its body A composed of a series of plane longitudinal faces, *a*, its lower end, B, enlarged, and provided with a series of faces, *b*, which correspond in number and relative position to those before named, while immediately below and around the upper

end of said body is placed a band, C, upon opposite sides of which are pivoted the ends of a bail, D, having upon its center an eye, *d*, that receives a ring, E.

Having thus fully set forth the nature and merits of my invention, what I claim as new is—

The design for a pencil-case, consisting of the body A, enlarged end B, swivel-band C, bail D, eye *d*, and ring E, substantially as shown.

In testimony whereof I hereunto set my hand this 30th day of October, 1873.

EDWARD TODD.

Witnesses:

Z. E. NEWELL,
W. J. WINBERG.
